UNITED STATES PATENT OFFICE

120,480

DESIGN FOR AN ICE TRAY

Clifford R. Carney, Detroit, Mich.

Application September 2, 1939, Serial No. 87,012

Term of patent 14 years

To all whom it may concern:

Be it known that I, Clifford R. Carney, a citizen of the United States, residing at Detroit, Wayne County, Michigan, have invented a new, original, and ornamental Design for an Ice Tray, of which the following is a specification, reference being had therein to the accompanying drawing, forming a part thereof, in which:

Fig. 1 is a perspective view of the ice tray, showing my novel design;

Fig. 2 is a side elevational view of the ice tray;

Fig. 3 is an end elevational view thereof; and Fig. 4 is a cross sectional view taken in the direction of the arrows on the vertical section plane passing through the line 4—4 of Fig. 1.

The dominant feature of the design resides in the grid portion shown in all of the above views in full lines.

I claim:

The ornamental design for an ice tray, substantially as shown and described.

CLIFFORD R. CARNEY.
